UNITED STATES PATENT OFFICE.

BEDELL PARKER, OF NEW YORK, N. Y.

PAJAMAS.

1,117,252.

Specification of Letters Patent. Patented Nov. 17, 1914.

Application filed February 13, 1914. Serial No. 818,500.

To all whom it may concern:

Be it known that I, BEDELL PARKER, a citizen of the United States, residing at New York, county of New York, and State of New York, have invented certain new and useful Improvements in Pajamas, of which the following is a specification.

This invention relates to pajamas.

The object of the present invention is the provision of an improved one-piece or union pajama which will obviate defects incident to earlier pajamas and may, in addition, be easily put on or taken off as a unit, will be comfortable, of attractive appearance, set well, hang freely and gracefully from the shoulders and be adapted for quick and convenient opening of the seat or posterior portion thereof without detaching the trousers from the jacket.

Another object is to provide a union or one-piece pajama whose jacket and trousers are permanently connected together, have a front opening from the neck to or near the crotch, the latter being permanently closed, and in addition, are provided with a seat opening which is normally overhung and covered by the rear skirt or lower part of the jacket, thereby obtaining the advantages incident to a one-piece garment without disclosing the seat construction when the wearer is walking about.

My invention consists, first, of pajamas whose trousers and jacket are connected together and whose jacket normally overhangs the seat or posterior part of the trousers, the latter having an opening, preferably providing a drop flap; second, pajamas composed of trousers and jacket which have an opening extending from the neck to or near the crotch thereof, the latter being permanently closed, and permanently seamed or sewed together at the front and a portion of the back of the trousers beneath or inside of the jacket, the remaining portion of the back, beneath the jacket, being provided with a crosswise extending opening which continues down the outside of one leg only of the trousers to a point above the lower end of the trousers leg, preferably below the closed crotch of the trousers, thereby providing a semi-drop flap seat, the rear, lower portion of the jacket completely covering the opening and drop flap seat last named, but being free therefrom.

One embodiment of the invention which is set forth hereinafter and disclosed in the drawings is to be considered as illustrative, rather than restrictive, of the scope of the invention.

In the accompanying drawings: Figure 1 is a front view with one part of the front of the jacket, and the fly, open; Fig. 2, a front view showing the entire front of the garment open and disclosing a portion of the back, one of the skirts of the jacket being thrown back; Fig. 3, a rear view with the back or skirt of the jacket in normal position, certain parts thereof being broken away to disclose the upper part of the drop flap seat; Fig. 4, a rear view showing the drop flap seat open and the rear skirt of the jacket raised; Fig. 5, a detail view of the opening extending partially across the back of the trousers and showing adjoining portions of the garment; and Fig. 6, a detail view of the crotch, as it appears when spread out.

The jacket or coat 1 may be of any usual or preferred construction or appearance except in its relation to the trousers as will appear more fully hereinafter. The jacket is provided with the usual front opening 2 extending from the neck to the lower edge thereof, any suitable fastenings, such as buttons and buttonholes 3, being provided for closing said opening.

The trousers 4 which have a closed crotch are open at the front, as shown at 5, and provided with any suitable fastening devices, such as buttons and buttonholes 6. It is not necessary that the opening 5 constitute a straight line continuation of the opening 2 in the jacket as these openings may be offset from each other. The front parts of the trousers are permanently seamed to the inside of the front of the jacket at 7 and a portion of the rear of the trousers is seamed at 8 to the inside of the back of the jacket being there preferably reinforced by a strip or band for greater strength and durability. Originating at 9 is an opening 10 which extends across the remaining portion of the back of the garment underneath the rear portion or skirt 11 of the jacket and thence continuing at 12 down the outside of one of the trousers legs and terminating at 13, the remaining portion 14 of the trousers leg being closed. The point 13 is preferably located below the crotch 15 of the trousers and the latter is a closed crotch. The drop flap seat 16 provided by the openings 10 and 12, may be closed by a single fastening, such as a button and buttonhole 17 at the upper corner thereof. The remaining leg of the trousers is closed at both the inner and outer sides 5 thereof.

The skirt 11 of the jacket depends or hangs freely down over the drop flap seat and completely obscures the latter from view, and as the lower portion of the jacket is 10 completely free from the trousers at all points, they can be readily opened or closed or raised or lowered.

The trousers and jacket being permanently connected together, constitute a one-piece pajama which can be quickly and easily put on or taken off and will obviate all necessity for tightness around the waist, as customary with two-piece pajamas, and also prevent any rising of the jacket or its 20 bunching under the arms of the wearer when the latter is in a reclining posture.

The lower rear portion or skirt of the jacket obscuring the seat or posterior portion of the trousers, the advantages of a 25 seat opening are combined with those of a one-piece garment.

The drop flap seat of the present garment is of substantially the construction set forth in my earlier applications, Serial Nos. 30 791,046 and 813,920, and my joint application, Serial No. 785,341, and I do not, therefore, in the present application lay claim to this seat construction alone.

Having thus described my invention, what I claim as new and desire to secure by Letters Patent, is:—

Pajamas consisting of trousers having a permanently closed crotch, a front fly, and an opening in one of the legs thereof, affording access to the posterior portion of said 40 trousers, and a jacket adapted to open at the front but otherwise presenting a continuous and unbroken appearance at both its front and rear from its neck to its lower edge, the said jacket being composed of 45 single, continuous sections extending without interruption from its neck to its free extreme lower edge and joined to the trousers on its inside only and well above its lower edge at both the back and front 50 thereof, whereby the connection of the trousers to the jacket is invisible from the exterior of the garment and the freely depending rear portion of the jacket hangs over the seat portion of the trousers. 55

In testimony whereof, I hereunto affix my signature in presence of two witnesses.
